UNITED STATES PATENT OFFICE

2,540,987

CLAMP RAISING AND LOWERING MEANS
FOR SEWING MACHINESMichael McCann, Union, N. J., assignor to The
Singer Manufacturing Company, Elizabeth,
N. J., a corporation of New Jersey

Application March 2, 1948, Serial No. 12,504

17 Claims. (Cl. 112—110)

1

This invention relates to cyclically operated sewing machines such, for example, as button sewing machines, and more particularly to improvements therein which will facilitate the operation of the machine by relieving the operator of the necessity of manually raising and lowering the work-clamp of the machine for each sewing cycle.

A primary object of this invention is to provide, in an article attaching machine such as that shown in my United States patent application Serial No. 715,685, filed December 12, 1946, now Patent No. 2,495,069, dated January 17, 1950, i. e. one having a reciprocating and laterally vibrating needle-bar, means for automatically lowering the article-holding work-clamp, and the article carried thereby, upon the work at the beginning of the sewing cycle and for automatically raising the clamp, to break the thread and release the work, at the completion of the cycle.

Another object is to provide an improved automatic clamp actuating mechanism adapted to lower the work-clamp by the initial portion of the first downstroke of the needle-bar in a sewing cycle and to raise the work-clamp by the final portion of the last upstroke thereof, regardless of the fact that those two strokes of the needle-bar are effected in laterally spaced vertical planes.

In my prior United States Patent No. 2,300,585, November 3, 1942 there is shown, described and claimed an automatic clamp lowering and raising mechanism actuated by the reciprocatory movements of a non-vibratory needle-bar. One of the objects of this invention is to improve that mechanism so as to adapt it to a sewing machine provided with a needle-bar which has both reciprocatory and vibratory motions.

An automatic clamp actuating mechanism of this nature is ideal when the machine is fitted with a clamp adapted to hold flat buttons, as the flat button may be properly inserted into the clamp while the clamp is lifted. When the clamp is lowered upon the work, the button will be held in the proper position for the needle to enter the holes in the button. However, under certain conditions automatic raising and lowering of the clamp is not desirable. For example, when the machine is fitted with a shank-button clamp such as shown in the McCann United States Patent No. 2,131,012, September 20, 1938, the button cannot be properly inserted in the button-clamp while the clamp is in the raised position because, in that position, the button-holding arm of the clamp is retracted and does not engage the back of the button to hold the shank thereof in the button-supporting foot forming a part of the button-clamp.

The present invention, therefore, has as an

2

other object to provide conveniently actuated means for rendering the automatic clamp lowering and raising mechanism ineffective, or inoperative, and for maintaining it in an inoperative condition until automatic actuation of the clamp is again desired.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a rear side elevation of a button sewing machine embodying the present invention, with a side cover plate thereof removed and with the bracket-arm head in section.

Fig. 2 is an enlarged front end view of the machine shown in Fig. 1 with the major portion of the face plate of the bracket-arm head broken away.

Fig. 3 is an enlarged rear view, partly in section, of the bracket-arm head and a portion of the bracket-arm, the automatic clamp lifting mechanism being shown in full lines as shifted to an inoperative position.

Fig. 4 is a horizontal sectional view taken substantially on the line 4—4 of Fig. 3 with the bracket-arm shown in elevation.

Fig. 5 is an enlarged end view of the bracket-arm head with the face plate removed.

Fig. 6 is a fragmentary vertical sectional view of the bracket-arm head and parts associated therewith, the parts being in positions different from those shown in Fig. 3.

Fig. 7 is a detail horizontal sectional view taken substantially on the line 7—7 of Fig. 3.

Fig. 8 is a detail horizontal sectional view taken substantially on the line 8—8 of Fig. 2.

Fig. 9 is a detail perspective view of the means for maintaining the automatic clamp-lifting means in an inoperative condition when automatic lifting of the work-clamp is not desired.

Referring more specifically to the drawings, the invention is disclosed as embodied in an article attaching machine, having a frame comprising a bed 1, having a laterally extending work-supporting arm 1^a, a bracket-arm 2, consisting of a standard 3, secured to the bed 1, and an overhanging arm 4 terminating in open-face bracket-arm head 5 normally closed by a removable face-plate 5^a. The arm 1^a is of substantially inverted U-shape in cross section and is normally closed by a removable sheet metal cover 1^b having, at its outer end, a spring-pressed hinged cover 1^c. Journaled lengthwise of the arm 4 is a main or drive shaft 6 carrying

at its rear end, a pinion 7 driven from a gear 8 journaled on a stub shaft 9 secured in a stop-motion bracket 10 fixed to the standard 3. Fixed to the gear 8 is a driving pulley 11, adapted to be driven from any suitable source, by a belt not shown. Also secured to the gear 8 is a notched stop-motion cam 12 which cooperates with a spring-pressed plunger 13 to bring the machine to rest after a predetermined number of stitches have been made. A loose pulley 14 also is journaled on the shaft 9 beside the drive pulley 11 and has the driving belt shifted thereto when the machine is brought to rest by the stop-motion mechanism. The pitch diameter of the gear 8 is twice that of the pinion 7 and therefore that gear rotates at only one-half the speed of rotation of the pinion 7 and shaft 6 which latter have one rotation for each stitch forming cycle. Thus it will be apparent that due to the slower speed of rotation of the gear 8 and stop motion cam the machine may be brought to rest with materially less strain and shock than can machines in which the driving pulley and the stop-motion cam are carried directly by the main or needle-bar-driving shaft. The stop-motion is provided with a treadle-actuated starting lever 15 (Fig. 2) and is held in running position by a spring-pressed latch 16 until the latch is automatically tripped, after a predetermined number of stitches have been made, by one or more cam-lugs 17 carried by the rear face of a rotating cam wheel 18 driven from the shaft 6, as shown and described in my above mentioned application Serial No. 715,685.

Journalized on the arm 4, by vertically disposed studs 19 and 20, is an oscillatory U-shaped frame or gate 21. At its lower end, this frame is provided with a horizontally arranged forwardly projecting arm 22 which extends into the bracket-arm head and has formed integrally therewith a vertically disposed sleeve 23 in which is reciprocably mounted a needle-bar 24 carrying, at its lower end, an eye-pointed thread-carrying needle 25. Slidably mounted in the head 5, parallel to but at one side and slightly rearward of the needle-bar, is a guide-bar 26 on which is slidably mounted a tubular portion 27^a of a member 27. This member has a forked portion 27^b adapted to receive a slide-block 28 forming a part of a collar 29 clamped upon the upper portion of the needle-bar by a clamp screw 30. The collar 29 also carries an arm 31 which projects through a slot 5^b in the face plate 5^a and has therein a thread-eye 32. This arm 31 and eye 32 form a part of a thread take-up mechanism which is shown and described more fully in my above mentioned application.

Vertical reciprocations are given to the member 27, on the bar 26, by endwise movements of a link 33 journaled at its upper end upon a pin 34 carried by the member 27 and embracing, at its other end, a crank-pin 35 carried by a crank-disk 36 secured upon the forward end of the rotary main shaft 6. The reciprocations of the member 27 are transmitted to the needle-bar and the needle carried thereby by the forked portion 27^b, slide block 28 and collar 29.

Cooperating with the needle, in the formation of stitches is a loop-taker 37, preferably in the form of a wing-type rotary chain stitch looper secured to and rotated by a loop-taker shaft 38. This shaft may be rotated from the shaft 6 by any suitable mechanism such, for example, as that disclosed in my above mentioned application.

Oscillation of the frame 21 for laterally shifting or vibrating the needle-bar transversely of the work-supporting arm 1^a to cause the needle successively to enter spaced holes in a button is effected from a cam groove 39 formed in one face of the cam wheel 18 hereinbefore mentioned. The specific means for transmitting motion from the cam groove 39 to the frame 21 forms no part of this invention and is designated generally as 10 x. Reference may be had to my above mentioned application for a more complete description thereof.

Mounted upon the upper surface of the work-supporting arm 1^a is a work-holder comprising 15 a work-plate 40 and an overlying button-clamp 41. The button clamp illustrated is adapted to hold flat buttons but it is to be understood that other forms of clamps may be substituted therefor, such for example as the shank-button clamp disclosed in my above mentioned Patent No. 2,131,012, September 20, 1938. The button clamp may be shifted lengthwise of the work-supporting arm by the mechanism disclosed in my above mentioned application or by any other 20 suitable means.

Secured to the upper side of the button-clamp is a fork 42 which embraces a stud 43 carried by an arm 44 projecting laterally from a collar 45. This collar is secured upon the lower end of 25 a spring-depressed clamp-lifting and clamp-depressing bar 46 mounted for vertical movement in the bracket-arm head 5. A coil spring 47 interposed between a wall of the bracket-arm head and a collar 48, secured upon the bar 46, normally maintains the bar and the button-clamp depressed. The collar 48 carries a depending arm 49 having an off-set stud-like portion 50. The bar 46 and the button-clamp connected therewith may be lifted, in opposition to the spring 47, by 30 a treadle-actuated lever 51, fulcrumed on a shoulder screw 52 threaded into a bracket 53 secured to the under side of the overhanging bracket-arm. The lever 51 has a forked end 51^a which engages the stud 50. 35 The collar 45 carries a forwardly projecting arm 54 formed integrally with a split collar 55, clamped upon the lower end of the guide-bar 26 hereinbefore mentioned. Thus the downward pressure exerted by the spring 47 is transmitted to the guide-bar 26 to urge it downwardly. Inasmuch as the guide-bar is rigidly connected with the button-clamp the two move in synchronism. Therefore when the button clamp is lowered by the spring 47 the slide-bar 26 is similarly moved 40 downwardly. Likewise when the slide-bar is moved upwardly, by means hereinafter to be described, the button clamp is raised in opposition to the spring 47.

Means, now to be described, is provided for 45 shifting the slide-bar 26 upwardly, thereby raising the button-clamp during the final upstroke of the needle-bar in each article attaching cycle. Clamped upon the slide-bar 26, within the bracket-arm head 5, is a collar 56 carrying a shoulder screw 57, upon which is journaled the lower end of a vertically disposed latch member 58. At its upper end the latch member 58 is formed with an off-set portion 58^a adapted, at certain times, to lie in the path of reciprocation 50 of a shoulder portion 27^b of the member 27, as shown in Figs. 5 and 6. When the parts are in this position upward movement of the member 27, which carries with it the needle-bar 24, will lift the latch member, bar 26, arm 54, collar 45 55 and stud 43 and thereby the button-clamp. The

latch member 58 is formed with a vertically disposed slot 58^b through which passes the reduced forward end portion 59^a of a lengthwise movable push-pull rod 59 which extends lengthwise of the arm 4, passing through an aperture 5^d in the rear wall 5^c of the bracket-arm head. Nuts 60, 61 threaded on the reduced portion 59^a, engage opposite faces of the latch member 58 and cause that member to be swung about its pivot 57 by the endwise movements of the rod 59. A coil spring 62, surrounding the rod 59 and interposed between the wall 5^c of the bracket-arm head and the nut 60, normally tends to shift the rod and the latch lever toward the right as seen in Figs. 1 and 4, to the position illustrated in those figures.

At its rear end the rod 59 is pivotally connected, by a coupling 63, to the upper arm 64^a of a two-armed lever 64 fulcrumed on a stud 64^c threaded into the bracket-arm. The action of the coil spring 62 normally urges lever 64 to turn in a clockwise direction, Figs. 1 and 3, thereby causing the free end of the lower arm 64^b of the lever 64 to bear against the periphery of the rotating cam wheel 18, hereinbefore mentioned. Secured to the periphery of the cam wheel 18, 180 degrees apart, are cam blocks 65 adapted to ride under the free end of the lower arm 64^b of the lever 64 after the stop-motion has been tripped to initiate the stopping of the machine near the completion of a sewing cycle. The cam block 65 turns the lever 64, counterclockwise, thereby shifting the rod 59 and latch member 58 from the position shown in Fig. 1 to the position shown in Fig. 6 thereby swinging the offset portion 58^a of the latch member 58 into the path of reciprocation of the shoulder 27^c of the member 27 as that member and the needle-bar start their final upward movements, at the end of a sewing cycle. Thereafter the final upward movement of the member 27 lifts the latch member 58 and thereby the button-clamp as hereinbefore described.

At the beginning of the next sewing cycle, the first downward movement of the member 27 and needle-bar 24 permits the latch member 58, guide-bar 26, arm 54, and the bar 46 to descend under the influence of the spring 47 thereby lowering the button-clamp upon a work-piece on the work-plate 49, as the cam block 65 moves beyond the lever arm 64^b.

From the foregoing it will be understood that the mechanism hereinbefore described will cause the work-clamp automatically to be lowered upon the work during the first downstroke of the needle-bar at the beginning of each sewing cycle and to be automatically lifted during the last upstroke of the needle-bar at the completion of each cycle. Due to the fact that the raising and lowering of the work-clamp is effected by the member 27 and not directly by the needle-bar the lateral vibratory movements of the needle-bar do not in any way interfere with the proper functioning of the automatic clamp lifting and lowering mechanism.

Under certain conditions, such, for example, as when using the machine to sew shank buttons, it may be desirable to render the automatic clamp lifting and lowering mechanism ineffective. This may be readily accomplished as now will be described. Slidably mounted on the reduced forward end portion 59^a of the rod 59 is a cylindrical push-button 66 having a knurled outer portion by means of which the push-button may be rotated relative to the rod 59. The push-button projects through an aperture 67 in the face-

plate 5^a. This aperture is generally circular but has an offset square portion 68 (Fig. 9) through which is adapted to slide a stop-block 69 secured to the side of the push-button. An annular flange 70 formed on the push-button is adapted to engage the inner surface of the face-plate to prevent withdrawal of the push-button through the aperture 67.

During the operation of the machine, when using the automatic clamp lifting mechanism, the push-button 66 is in its outermost position i. e. with its flange 70 in contact with the inner surface of the face plate and with the stop-block 69 projecting through the square portion 68 of the aperture 67, all as illustrated in Figs. 1, 4 and 8 and in dotted lines in Fig. 3. In this position the push-button has no effect on the automatic clamp lifting mechanism and that mechanism operates as hereinbefore described.

When it is desired to render the automatic clamp lifting mechanism inoperative, the push-button 66 is pushed inwardly, in opposition to the spring 62, from the position shown in Figs. 1, 4 and 8, and given a partial rotation to place the outer end of the block 69 behind the inner surface of the face plate 5^a, as shown in Figs. 3 and 9. This inward movement of the push-button shifts the rod 59, latch member 58 and lever 64 to the positions shown in full lines in Fig. 3 i. e. with offset portion 58^a of the latch member 58 out of the path of movement of the shoulder portion 27^c of the member 27 and the free end of the arm 64^b of the lever 64 out of the path of rotation of the cam blocks 65 on the cam wheel 18. With the parts in the positions shown in Fig. 3 the machine may complete its sewing cycle and be brought to rest by the stop motion mechanism without effecting lifting or lowering of the button clamp.

To again render the automatic clamp lifting means effective it is merely necessary to rotate the push-button sufficiently to align the block 69, carried thereby, with the offset square portion 68 of the aperture 67 whereupon the expansion of the spring 62 will move the rod 59 endwise and shift the parts into their operative positions.

Having thus set forth the nature of the invention, what I claim herein is:

1. A sewing machine having, in combination, a reciprocatory and laterally vibratory needle-bar adapted to have reciprocations in laterally spaced paths; a work-clamp; a member having a horizontal sliding connection with the needle-bar and mounted for vertical reciprocation in a fixed path at each reciprocation of said needle-bar; a stop-motion device constructed and arranged to bring the machine to rest at the completion of a predetermined sewing cycle; and a normally ineffective coupling element and means for actuating said element in timed relation with said stop-motion device to cause it to couple said member to said work-clamp for automatic lifting of the latter as the machine comes to rest.

2. A sewing machine having, in combination, a reciprocatory and laterally vibratory needle-bar adapted to have reciprocations in laterally spaced paths; a spring-depressed work-clamp; a member having a horizontal sliding connection with the needle-bar and mounted for vertical reciprocation in a fixed path at each reciprocation of said needle-bar; a stop-motion device constructed and arranged to bring the machine to rest at the completion of a predetermined sewing cycle; and a normally ineffective coupling element and means for actuating said element in timed relation with said stop-motion device to cause it to couple said member to said work-clamp for automatic lifting of the latter as the machine comes to rest.

cycle; means including a rotary element for controlling the action of said stop-motion device; and coupling means actuated by said rotary element and operating in timed relation with said stop-motion device to couple said member to said work-clamp for automatic lifting of the latter during the final upward movement of the needle-bar.

3. In a sewing machine having a head, a vertically reciprocatory and laterally vibratory needle-bar mounted in said head, means for reciprocating and vibrating said needle-bar, a work-clamp, and a stop-motion device constructed and arranged to bring the machine to rest at the completion of a predetermined sewing cycle; the improvement which consists in the provision of a slide-bar mounted in said head and connected with said work-clamp; a member slidably mounted on said slide-bar and reciprocating with said needle-bar; and means operated in timed relation with said stop-motion device to connect said member to said slide-bar for automatically lifting said slide-bar and work-clamp at the completion of the sewing cycle.

4. In a sewing machine having a head, a vertically reciprocatory and laterally vibratory needle-bar mounted in said head, means for reciprocating and vibrating said needle-bar, a work-clamp, and a stop-motion device constructed and arranged to bring the machine to rest at the completion of a predetermined sewing cycle; the improvement which consists in the provision of a slide-bar mounted in said head and connected with said work-clamp; a member slidably mounted on said slide-bar and reciprocating with said needle-bar; a latch member pivotally secured to said slide-bar and normally maintained out of the path of reciprocation of said member; and means operated in timed relation with said stop-motion device to shift said latch-member into the path of reciprocation of said member to cause said member to lift said slide-bar and work-clamp at the completion of the sewing cycle.

5. In a sewing machine having a head, a vertically reciprocatory and laterally vibratory needle-bar mounted in said head, means for reciprocating and vibrating said needle-bar, a work-clamp, and a stop-motion device constructed and arranged to bring the machine to rest at the completion of a predetermined sewing cycle; the improvement which consists in the provision of a slide-bar mounted in said head and connected with said work-clamp; a member slidably mounted on said slide-bar and reciprocating with said needle-bar; a shoulder provided by said member; a latch member pivotally secured to said slide-bar and having an offset portion; and means operated in timed relation with said stop-motion device to swing said latch member into a position in which said offset portion overlies said shoulder to cause said member to lift said slide-bar and work-clamp at the completion of the sewing cycle.

6. A cyclically operated article-attaching machine combining a head; a pivotally mounted article-holding clamp; stitch-forming mechanism including a reciprocating needle-bar mounted in said head; a clamp-lifting bar slidably mounted in said head and connected with said clamp; a clamp-lifting member slidably mounted on said bar; means connecting said member with said needle-bar for reciprocation therewith; a latch member pivotally secured to said bar; spring

means acting on said latch member for holding it out of the path of reciprocation of said clamp-lifting member; and means acting in opposition to said spring means for shifting said latch member into the path of movement of the clamp-lifting member during the final upward movement of the needle-bar in each sewing cycle.

7. In a sewing machine having a head, a vertically reciprocable and laterally shiftable needle-bar mounted in said head, means for reciprocating said needle-bar, means for shifting said needle-bar laterally between successive reciprocations thereof, a work-clamp, and a stop-motion device constructed and arranged to bring the machine to rest at the completion of a predetermined sewing cycle; the improvement which consists in the provision of a clamp lifter located in said head and connected with said work-clamp; a member slidably mounted on said clamp lifter and having a sliding driving connection with said needle-bar in all lateral positions of the needle-bar; and means operated in timed relation with said stop-motion device to connect said member to said clamp lifter for actuating said clamp lifter to cause it to lift said work-clamp by the final upward movement of the needle-bar at the completion of a sewing cycle.

8. A sewing machine combining a reciprocatory needle-bar; a work-clamp; a stop-motion device constructed and arranged to bring the machine to rest at the completion of a predetermined sewing cycle; automatic means including a shiftable member operated in timed relation with the stop-motion device to couple said needle-bar to said work-clamp for automatically lifting the latter as the machine comes to rest; and a manually operated element for holding said shiftable member out of operative position to render said automatic means ineffective.

9. A sewing machine combining a reciprocatory needle-bar; a work-clamp; a stop-motion device constructed and arranged to bring the machine to rest at the completion of a predetermined sewing cycle; automatic means including a spring-biased latch member operated in timed relation with the stop-motion device normally to couple said needle-bar to said work-clamp for automatic lifting of the latter by the last up-stroke of the needle-bar in a sewing cycle; and a manually operated element for shifting said latch member to an inoperative position to render the latch member ineffective to couple said needle-bar to said work-clamp.

10. A sewing machine combining a reciprocatory and laterally vibratory needle-bar adapted to have reciprocations in laterally spaced paths; a work-clamp; a member mounted for vertical reciprocation in a predetermined path at each reciprocation of said needle-bar; a stop-motion device constructed and arranged to bring the machine to rest at the completion of a predetermined sewing cycle; coupling means operated automatically in timed relation with said stop-motion device to couple said member to said work-clamp for effecting automatic lifting of the latter as the machine comes to rest; and manually actuated means for shifting said coupling means out of the path of movement of said member rendering said automatic clamp-lifting means ineffective.

11. A cyclically operated sewing machine combining a head; a pivotally mounted article-holding clamp; stitch-forming mechanism including a reciprocating needle-bar mounted in said head; a

clamp-lifting bar slidably mounted in said head and connected with said clamp; a clamp-lifting member slidably mounted on said bar; means connecting said member with said needle-bar for reciprocation therewith; a latch member secured to said clamp-lifting bar and having a portion movable into the path of movement of said clamp-lifting member; spring means normally maintaining said latch member out of the path of movement of said clamp-lifting member; automatic means operating in opposition to said spring means for shifting said latch member into the path of movement of the clamp-lifting member during the final upward movement of the needle-bar in a sewing cycle; and manually actuated means for rendering said automatic means ineffective to lift the clamp.

12. A cyclically operated article-attaching machine combining a frame including a bracket-arm and a bracket-arm head; a pivotally mounted article-holding clamp; stitch-forming mechanism including a reciprocating needle-bar mounted in said head; a clamp-lifting bar slidably mounted in said head and connected with said clamp; a clamp-lifting member slidably mounted on said bar; means connecting said member with said needle-bar for reciprocation therewith; a latch member secured to said clamp-lifting bar; a rotary cycle-control member journaled on said frame; means actuated by said cycle control member and extending lengthwise of said bracket-arm for shifting said latch member into the path of movement of the clamp-lifting member during the final upward movement of the needle-bar in a predetermined sewing cycle, to effect automatic lifting of the button-clamp; and manually operable means for shifting said latch member out of the path of movement of said clamp-lifting member thereby to render said automatic clamp-lifting means ineffective.

13. A cyclically operated article-attaching machine, combining a frame including a bracket-arm and a hollow bracket-arm head; a face-plate secured to said head; a pivotally mounted article-holding clamp; stitch-forming mechanism including a reciprocating needle-bar mounted in said head; a clamp-lifting bar slidably mounted in said head and connected with said clamp; a clamp-lifting member slidably mounted on said bar; means connecting said member with said needle-bar for reciprocation therewith; a latch member secured to said clamp-lifting bar; a cam-actuated rod extending lengthwise of said bracket-arm for shifting said latch member into the path of movement of the clamp-lifting member during the final upward movement of the needle-bar in a predetermined sewing cycle to effect automatic lifting of the work-clamp; and a manually operable member carried by said face-plate for shifting said latch member out of the path of movement of said clamp-lifting member to render the automatic clamp-lifting means ineffective.

14. A cyclically operated sewing machine combining a head; a face-plate secured to said head; a pivotally mounted work-clamp; stitch-forming mechanism including a reciprocating needle-bar mounted in said head; a clamp-lifting bar slidably mounted in said head and connected with said clamp; a latch member secured to said clamp-lifting bar and normally disconnected

from said needle-bar; automatically actuated means for shifting said latch member to cause it to connect said needle-bar with said clamp-lifting bar during the final upward movement of the needle-bar in a sewing cycle; and manually operable means carried by said face-plate to shift said latch member to an ineffective position thereby to render said automatically actuated means inoperative.

10 15. In a sewing machine having a head, a vertically reciprocating needle-bar mounted in said head, means for reciprocating said needle-bar, a work-clamp, and a stop-motion device constructed and arranged to bring the machine to rest at the completion of a predetermined sewing cycle; the improvement which consists in the provision of a slide-bar mounted in said head and connected with said work-clamp; a member slidably mounted on said slide-bar and reciprocating with said needle-bar; a latch lever pivotally mounted on said slide-bar and normally biased to one of two extreme positions in which it is out of the path of reciprocation of said member; means operated in timed relation with said stop-motion device to shift said latch lever into an intermediate position and in the path of reciprocation of said member to connect said member to said slide-bar for automatically lifting said slide-bar and work-clamp by the last upstroke of the needle-bar at the completion of the sewing cycle; and manually actuated means for shifting said latch lever to its other extreme position and for locking it in the last named position to render the automatic clamp-lifting means ineffective.

16. In an article-attaching machine having stitch-forming mechanism including a reciprocating needle-bar, an article-holding clamp, and means including a latch member actuated by the needle-bar during one only of a predetermined plurality of upward movements thereof for automatically lifting the article-holding clamp; the improvement which comprises the provision of a manually operated element engaging said latch member for shifting it to an inoperative position to render said clamp-lifting means ineffective.

17. In a cyclically operated article-attaching machine, in combination, a head; stitch-forming mechanism including a reciprocating needle-bar mounted in said head; a member reciprocated with said needle-bar; an article-holding clamp; automatic clamp-lifting means including a latch element connected with said clamp and adapted to be swung into the path of movement of said member during the final upstroke of the needle-bar for normally causing the needle-bar to lift the clamp; and a push button mounted in said head and constructed and arranged to act on said latch element to hold it out of the path of movement of said member to render the automatic clamp-lifting means ineffective.

MICHAEL McCANN.
